CLAIM

The ornamental design for a clock, as shown and described.

DESCRIPTION

FIG. 1 is a top, front, right perspective view of a clock in accordance with my design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a rear elevational view thereof.

The broken lines represent parts of the clock that form no part of the claimed design.
